(57) CLAIM

I claim the ornamental design for a large law enforcement privacy screen that is foldable for vehicle trunk storage, as shown and described.

DESCRIPTION

FIG. 1 is a perspective view of a large law enforcement privacy screen that is foldable for vehicle trunk storage showing my new design;

FIG. 2 is a front elevational view thereof;

FIG. 3 is a rear elevational view thereof;

FIG. 4 is an end elevational view thereof, the elevational view of the opposing end being identical thereto;

FIG. 5 is a top plan view thereof, the bottom plan view being identical thereto; and,

FIG. 6 is a reduced perspective view showing the large law enforcement privacy screen that is foldable for vehicle trunk storage in use.

The broken lines depict environmental structure for illustrative purposes only and form no part of the claimed design.
